FENCE POST CAP

Richard E. Savin, Chicago, Ill., assignor to Sears, Roebuck and Co., Chicago, Ill., a corporation of New York

Application November 29, 1956, Serial No. 43,986

Term of patent 14 years

(Cl. D28—1)

Fig. 1 is a side elevational view of a fence post cap embodying my new design;

Fig. 2 is a top plan view thereof; and

Figs. 3 and 4 are fragmentary vertical sectional views of the same taken along the lines 3—3 and 4—4, respectively of Fig. 2.

I claim:

The ornamental design for a fence post cap, as shown.
